(57) **CLAIM**

We claim the ornamental design for a golf club head, as shown.

DESCRIPTION

FIG. 1 is a front elevational view of a golf club head embodying our new design.

FIG. 2 is a rear elevational view of the golf club head of FIG. 1.

FIG. 3 is a magnified view of a portion of the rear surface of the golf club head of FIG. 1.

FIG. 4 is a cross-sectional view of the portion of the rear surface of FIG. 3, taken in the direction of the arrows 4—4 in FIG. 3.

FIG. 5 is a left side elevational view of the golf club head of FIG. 1.

FIG. 6 is a right side elevational view of the golf club head of FIG. 1.

FIG. 7 is a top plan view of the golf club head of FIG. 1.

FIG. 8 is a bottom plan view of the golf club head of FIG. 1.

FIG. 9 is a front perspective view of the golf club head of FIG. 1; and,

FIG. 10 is a rear perspective view of the golf club head of FIG. 1.

The dashed lines are for illustrative purposes only and form no part of the claimed design.
